UNITED STATES PATENT OFFICE.

EUGENE GASE, OF SAGINAW, MICHIGAN, ASSIGNOR TO BAKER-PERKINS MANUFACTURING CORPORATION, OF SAGINAW, MICHIGAN.

BAKER'S PROPORTIONATE FLOUR FEEDER AND MIXER.

1,383,798.

Specification of Letters Patent. Patented July 5, 1921.

Application filed December 4, 1920. Serial No. 428,836.

To all whom it may concern:

Be it known that I, EUGENE GASE, a citizen of the United States, residing at Saginaw, in the county of Saginaw and State of Michigan, have invented new and useful Improvements in Bakers' Proportionate Flour Feeders and Mixers, of which the following is a specification.

In most large bakeries and many similar industrial establishments very large quantities of different kinds of powdery materials as flour, chemicals, pigments, etc., are daily proportioned, that is weighed or measured in the proportionate quantities necessary for a process, and then mixed which operations require a great amount of labor, supervision and time and machinery spreading over a considerable space and usually two floors. My invention relates to improvements in apparatus used for this purpose and has for its object to make the operation automatic and more effective, and thus to save labor, supervision and time, and to confine it to the same floor and to as small a space as possible.

To this end I divide a wide and low hopper, resting on the floor of the workroom, by adjustable partition walls into as many compartments as there are materials to be proportioned, and construct its bottom of a series of horizontal rollers extending vertically to the partition walls throughout the whole width of the hopper. The outlet of the latter is situated above the last roller at one side, and its height and size and thereby the quantity of materials delivered from the hopper are regulated by means of an adjustable shutter. The rollers the axes of which are placed in one and the same plane, either horizontal or slightly inclining toward the outlet, are slowly rotated in the direction of the latter. After the different compartments have been duly adjusted and charged, the materials—different in each one—will then be carried away through the outlet in a broad completely even and at all points equally high layer and thus proportioned as required, the action of the rollers equalizing the amount of the delivery from the compartments, may all be equally filled or not, and may each one be completely or partly charged. The stream of proportioned materials which leaves the outlet continuously as long as the compartments are kept

filled, then slides down a short incline into the well of a quickly rotating elevator arranged parallel to and slightly wider than the outlet of the hopper. The chains of the elevator are provided at regular and equal intervals with horizontal rods fitting in length to the well, and each carrying rigidly affixed thereto one bucket or a small number of buckets all of which are of the same size and shape for the same elevator. These buckets are arranged stepwise at consecutive rods so as to cover the whole width of the elevator well so that during the time, in which the number of buckets and rods necessary to do so pass through the well, they lift from the latter the various materials in the same proportion as they entered the same, and also in a quantity equal to that leaving the hopper in the same interval of time, provided the elevator is worked quickly enough for attaining this purpose. If only one bucket is affixed to a rod, the number of stepwise arranged buckets necessary for covering the width of the well will require an equal number of consecutive rods, and, if several buckets are attached to one rod, they must be evenly in equal distances distributed along the same, and the number of consecutive rods necessary for the buckets attached thereto extending along the whole length of the well will be equal to the number of the rods necessary, if only one bucket were attached to each, divided by the number of the buckets actually attached to one rod. The total number of rods for this elevator must always be a multiple of the number of those necessary for the buckets attached thereto to cover the whole width of the well. It has been proved to be of advantage that the buckets arranged in this manner at a consecutive row of rods slightly overlap each other. The materials raised by the buckets drop on their downward passage quickly and successively into a hopper preferably provided with baffles or similar means for attaining a dispersion and intermingling of the materials entering the same; a screw conveyer or similar device carries then the mass thus correctly proportioned and mixed to its destination, usually a sifter or bin arranged on the same floor.

The accompanying drawings serve for further explaining my invention.

Figure 1 is a sectional elevation of the

proportioning device, the elevator and the hopper receiving the materials from the latter.

Fig. 2 is a plan view of the rollers at the bottom of the proportioning hopper.

Fig. 3 shows diagrammatically the arrangement of the rods and buckets of the elevator passing upward as at the right side of the same in Fig. 1.

Fig. 4 is a vertical cross section on the line 4—4 of Fig. 1, showing especially the arrangements for regulating the position of the partition walls for proportioning the various materials, the receiving hopper with baffle plates and screw conveyer and the arrangement of the gearing for driving the hopper rollers and the elevator.

Fig. 5 gives a side view of the apparatus, showing the driving gear, on the front side in dark and on the back side in dotted lines, and the adjusting arrangement for the shutter of the proportioning hopper; and Fig. 6 is an enlarged representation of this adjusting device.

Throughout these views like numerals of reference indicate corresponding parts serving the same or a similar purpose.

1 designates the proportioning hopper and 2 the elevator with the receiving hopper 3. The hopper 1 comprises two side walls 4 sloping in the same direction, the front wall 5; the back wall 6 parallel to 5, the eight horizontal and parallel rollers 7 arranged vertically to the walls 5 and 6 and forming the bottom of 1, the five partition walls 8 and the outlet 9 the height of which is regulated by the shutter 10. The rollers 7 are of wood and provided at their ends with coaxial iron shafts revolvably supported in bearings fitted in the walls 5 and 6, the wall 5 carrying the shafts 11 and the wall 6 the shafts 12. The axes common to these shafts and to the rollers 7 lie in the same even plane which is either horizontal or very slightly declining toward the outlet 9. The partition walls 8 are usually made of strong iron plate, follow the outlines of the side walls 4 and of the top of the rollers 7, are arranged parallel to the walls 5 and 6 and slidably supported by the two rods 13 vertically fixed to these walls. Each partition wall 8 is fitted with two flanges 14 tightly sliding on the rods 13 and arranged so as to keep it always parallel to the walls 5 and 6; after having been adjusted according to requirements, the walls 8 are fixed to the rods 13 by means of the screwbolts 15. A suitable scale 16 is provided just above the hopper for facilitating the exact adjustment of the walls 8. For making the delivery even all along the width of the outlet opening 9, the lower edge of the shutter 10 must be exactly parallel to the top of the roller 7 above which it is situated; in order to retain the shutter in this position during ad-

justment and for making the latter as fine as possible, a special gear is provided; to the upper end of the shutter 10 two short rods 17 are fixed, protruding over the walls 5 and 6 and having screw threaded openings 70 meshing with the screw pins 18 revolvably mounted in the brackets 19 and 20 fixed to supports 21 arranged at the machine; the upper ends of the pins 18 are fitted with the bevel-wheels 22 meshing with the bevel 75 wheels 23 fixed to the shaft 24 revolving in bearings arranged on the supports 21 and worked by means of the handwheel 25.

The five partition walls 8 provide 6 separate chambers in the hopper 1 so that six 80 different powders may be proportioned therein. After adjusting and fixing the wall 8 and the shutter 10, the chambers are filled and the rollers 7 slowly rotated in the direction of the outlet 9; the materials duly proportioned will then flow in an even and regular stream from over the last roller 7 down the incline 26 into the well 27 of the elevator 2.

The elevator 2 comprises the two upper 90 and larger sprocket wheels 28 fixed to the shaft 29, the two lower and smaller sprocket wheels 30 fixed to the shaft 31, the two chains 32 running over these sprocket wheels, twenty rods 33 horizontally affixed to the chains 32 and forty buckets 34, two attached to each rod 33. The shafts 29 and 31 are rotatably supported by bearings arranged in the housing 35 of the elevator 2 and placed so that the upward moving half of the chains 100 32 is vertical and farthest away from the receiving hopper 3, while the downward traveling half is slanting away from the latter in such a manner that the upmost buckets, when turning downward with their 105 rod on the wheels 28, are ready to drop their contents across the edge of the wall 36, situated between the elevator 2 and the hopper 3, into the latter. The buckets 34 (Fig. 3) are of such a size that ten cover the whole 110 length of a rod 33 and thus of the well 27, while slightly overlapping each other; five rods 33, each having two buckets attached thereto, are therefore necessary to do the same. The back wall 37 of the hopper 3—opposite to the wall 36—is vertical, and the side walls 38 are slanting downward to a small half circular well 39 in which the screw conveyer 40 rotates, carrying the finished mass away from the machine; baffles 115 41 serve to intermingle the materials on their passage down from the buckets into the hopper 3. The elevator 2 and the rollers 7 rotate in opposite direction to each other. The shaft 29, the driving shaft of the elevator 2, is rotated by means of the power pulley 42 fixed thereto; on its opposite end the shaft 29 carries the small gear wheel 43 meshing with the comparatively very large gear wheel 44 mounted on the countershaft 120 125 130

45; the latter is supported by bearings arranged in the sides of the housing 35 and carries at one end the sprocket wheel 46 driving by means of the chain 47 the 5 sprocket wheel 48, and at its other end the sprocket wheel 49 driving by means of the chain 50 the sprocket wheel 51. The sprocket wheel 48 is fixed to the shaft 11 of the last roller 7 situated underneath the outlet 9; to the same shaft the sprocket wheel 52 is attached, driving by means of the continuous chain 53 the three sprocket wheels 54 of equal diameter fixed to the shafts 11 of the three alternately following rollers 7; 10 the sprocket wheel 51 is mounted on the shaft 12 of the last but one roller 7 and drives by means of the sprocket wheel 55 attached to the same shaft and the chain 56 the three sprocket wheels 57 of equal diameter mounted on the shafts 12 of the three alternately following rollers 7. In the machine shown the shaft of the elevator 2 makes 10 revolutions in the same time in which the rollers make only one.

25 I claim:

1. In a machine for the purpose described, in combination a wide hopper, rotatable parallel rollers having approximately the same diameter and forming the 30 bottom of the said hopper, partition walls arranged vertically to the said rollers so as to form with the side walls of the said hopper as many compartments as there are different materials to be proportioned, means 35 for adjusting the said partition walls sideways so as to regulate the size of the said compartments, an outlet for the proportioned materials arranged closely above the last of the said rollers and extending along 40 its whole length, means for rotating all the said rollers at the same time with equal celerity and in the direction of the said outlet, and means for mixing the proportioned materials leaving the latter.

45 2. In a machine for the purpose described, in combination a wide hopper, adjustable partition walls arranged therein, a conveying device forming the bottom of the said hopper, an outlet arranged in the latter closely above and having the same width as the said conveying device, means for moving the latter in the direction of the said outlet, a well adapted to receive the broad stream of materials coming from the said 50 outlet, a bucket elevator the buckets of which are arranged stepwise thereon so as to remove successively and in regular intervals the consecutive portions of the materials in the well from one end of the same 55 to the other, and means for working the elevator in accordance with the quantity of materials delivered into the said well by the said conveying device.

60 3. In a machine for the purpose described, in combination a wide and low hop-

65 per having four sides, two vertically arranged and parallel to each other, and two connecting the first two and sloping in the same direction, a plurality of rollers forming the bottom of the said hopper and placed with their axes vertically to the vertical sides of the said hopper and in one plane, adjustable partition walls arranged in the said hopper parallel to its vertical sides and following in outline its sloping 70 sides and the top of the said rollers, an outlet for the said hopper cut out of that of its sides sloping out from over the last roller and just above and in the whole length of the latter, an adjustable shutter adapted to 75 regulate the height of the said outlet parallel to the said last roller, and means for slowly rotating the said rollers all at the same time and at the same speed.

4. In a machine for the purpose de- 80 scribed, in combination a wide and low hopper, a plurality of parallel rollers forming the bottom of the said hopper, an adjustable outlet for the materials from the said hopper, situated above and parallel to the last 85 of the said rollers, adjustable parallel partition walls arranged in the said hopper vertically to the said outlet, means for slowly rotating all the said rollers at the same time, a well having the same width as the 90 said outlet, an incline connecting the former with the latter, an elevator having the same width as the said well and raising successively and in regular intervals from each portion of the same the materials in the same 95 proportion as they leave the said outlet, and means for quickly rotating the said elevator.

5. In a machine for the purpose de- 100 scribed, in combination an oblong rectangular hopper, adjustable partition walls parallel to the two shorter side walls of the said hopper, a conveying device forming the bottom of the said hopper, an outlet arranged in one of the longer side walls of the said hopper closely above and parallel to the 105 said conveying device and extending along its whole width, means for moving the said conveying device in the direction of the said outlet, a well arranged underneath the said outlet and in its whole width, a bucket elevator the buckets of which are attached stepwise to rods, fixed at regular intervals to the elevator chains parallel to the said well, and so adapted and arranged that the buckets attached to a number of consecutive rods extend—combined sideways—across the whole width of the well, this number being equal throughout the elevator, and the total number of rods employed being a multiple thereof, and means for working the said elevator so 110 as to remove the materials from the said well as quickly as they are delivered into the same by the said conveying device.

6. In a machine for the purpose de- 115 scribed, in combination with a hopper hav-

ing an outlet delivering the materials proportioned therein in a broad and low stream, of a well of the same width for receiving the said stream, of an elevator comprising two rotary shafts placed one above the other and supporting each two sprocket wheels arranged in line and meshing with two continuous chains running over them, of rods corresponding in length to the width 5 of the said well and fixed crosswise at equal intervals to the said two chains, and of buckets of equal shape and capacity rigidly fixed with their longest side to the said rods, a small number at regular intervals to each 10 rod, and arranged stepwise and evenly at a consecutive number of the same so as to cover the whole width of the said well as many times as there are buckets on each of the said rods, the total number of the latter 15 employed in the said elevator being a multiple of the said number of consecutive rods.

7. In a machine for the purpose described, the combination with a hopper having an outlet delivering the proportioned materials in a broad and low stream, of a well of the same width for receiving the said stream, of an elevator comprising an upper rotary shaft carrying two larger 20 sprocket wheels, a lower rotary shaft carrying two smaller sprocket wheels in line with the larger ones and two continuous chains meshing with and running over the said sprocket wheels, of rods corresponding in 25 length to the width of the said well and fixed crosswise at equal intervals to the said two chains, of buckets of equal shape and capacity attached stepwise with their longest side and at equal intervals to a consecutive number of the said rods in such a 30 manner as to cover the whole width of the said well, the total number of the said rods used in the said elevator being a multiple of the number necessary for the latter purpose, of a hopper wide at the top and narrow at the bottom, so adapted and arranged 35 at the elevator as to collect the materials successively dropping from the buckets when entering on their downward passage, 40 of baffles arranged in the last named hopper, and of a screw conveyer removing its contents from its lower end.

8. In a machine for the purpose described, in combination, a hopper, partition 45 walls therein, a conveying device forming the bottom of the said hopper, an outlet arranged closely above and parallel to the said conveying device and extending in its whole width, means for moving the conveying 50 device in the direction of the said outlet,

let, a well corresponding in width to the latter and adapted to receive the stream of materials leaving the same, a bucket elevator having the same width as the said well, its buckets being arranged stepwise thereon 55 so as to raise successively and in regular intervals the materials delivered by the said conveying device into the said well in consecutive portions from one end of the latter to the other, means for working the 60 said elevator to suit the quantity of materials in the said well, a hopper arranged alongside the said bucket elevator and so adapted and arranged as to receive the materials raised by the said elevator, a mixing device arranged in the last named hopper, and means for conveying the material from the latter to their destination.

9. A machine for the purpose described, comprising a wide and broad hopper, a plurality of parallel rollers forming the bottom of the said hopper, adjustable partition walls parallel to each other and vertical to the said rollers, an outlet for the materials proportioned in the said hopper, situated above and parallel to the last of the said rollers and of the same width as the latter, an adjustable shutter adapted to regulate the height of the said outlet parallel to the said last roller, a well having the same width as the said outlet and adjacent to and connected with the same by a short incline, two rotary shafts, an upper and a lower one arranged above the said well, two larger sprocket wheels mounted on the upper shaft, two smaller sprocket wheels mounted on the lower shaft, both kinds being in line with each other, two continuous chains meshing with and running over the said sprocket wheels, rods corresponding in 80 length to the said well and fixed crosswise at equal intervals to the said chains, of buckets of equal shape and capacity fixed stepwise to a consecutive number of the said rods in such a manner as to cover the whole 85 width of the said well, the total number of the said rods used on the said chains being a multiple of the number necessary for this purpose, and the said sprocket wheels, chains, rods and buckets being arranged so that 90 they raise the proportioned materials from the said well and drop them in quick succession into a separate and adjacent hopper, and of driving gear adapted to drive the said rollers slowly in the direction of the 95 said outlet of the proportioning hopper and the said chains with their rods and buckets quickly away from this outlet.

EUGENE GASE.
